(57) **CLAIM**

The ornamental design for a cover for emergency equipment, as shown and described.

DESCRIPTION

FIG. 1 is a front view of a cover for emergency equipment, showing my new design.

FIG. 2 is a rear view thereof.

FIG. 3 is a right view thereof.

FIG. 4 is a left view thereof.

FIG. 5 is front left perspective view thereof; and,
FIG. 6 is rear left perspective view thereof.

The broken dash-dot-dash lines are boundary lines that form no part of the claimed design, which indicate a boundary between claimed portions and unclaimed portions. The broken dashed lines illustrate unclaimed portions of the design. Broken dashed lines at which solid lines terminate are also boundary lines which indicate a boundary between claimed portions and unclaimed portions.
